[57] CLAIM

The ornamental design for a survival capsule, substantially as shown.

DESCRIPTION

FIG. 1 is a schematic front elevation of a survival capsule embodying this invention;

FIG. 2 is a schematic side elevation of the survival capsule of FIG. 1;

FIG. 3 is a schematic rear perspective of the survival capsule of FIG. 1;

FIG. 4 is a schematic top plan view of the survival capsule of FIG. 1; and,

FIG. 5 is a schematic bottom plan view of the survival capsule of FIG. 1.
